CLAIM

The ornamental design for an infrared receiver, as shown and described.

DESCRIPTION

FIG. 1 is a front perspective view of an infrared receiver; FIG. 2 is a rear perspective view of the infrared receiver; FIG. 3 is a front elevational view of the infrared receiver; FIG. 4 is a rear elevational view of the infrared receiver; FIG. 5 is a top plan view of the infrared receiver; FIG. 6 is a bottom plan view of the infrared receiver; FIG. 7 is a left side elevational view of the infrared receiver; and, FIG. 8 is a right side elevational view of the infrared receiver.

Shades appearing on the surfaces of the article in each photograph are reflection shadows due to lighting used for photography or three-dimensional shape of each part of the article and form no part of the claimed design.
